UNITED STATES PATENT OFFICE.

HARRY H. VICKERS, OF CORONA, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed October 10, 1925. Serial No. 61,662.

This invention relates to interponent or shield devices for typewriting machines, for preventing certain characters typed on a work-sheet from being carbon-copied on an underlying record-sheet, and is in the nature of an improvement on the device disclosed in the application of J. A. B. Smith, Serial No. 60,190, filed October 3, 1925. They may be advantageously used for typewriting bank-checks and drafts arranged in sheet-form and for making a condensed record of them at the same time.

To save space on a check-register or record-sheet, it is desirable to have thereon but one line of record-data of a check, the payee's name and the numerical amount of the check, and have that line spaced nearer the preceding line of data on the record-sheet than it is on the overlying check-sheet. In said application, provision is made of means for accomplishing these results, which includes a paper-table mounted on a typewriter-carriage and having side flanges arranged for engagement in open slots, and a thin movable shield for guiding the same and limiting its upward movement; said shield being arranged to be interposed, at will, between a check-sheet and an underlying record-sheet, to prevent certain characters typed on the former from being carbon-copied on the latter.

In the present invention, provision is made of a paper-table mounted on a typewriter-carriage and having side flanges provided with narrow lengthwise slots through which may project lateral stop-pieces of the movable shield for limiting both its upward and downward movement when interposed between a check-sheet and its record-sheet below the printing line, for preventing certain characters typed on the latter being carbon-copied on the record-sheet. Limiting the downward movement of the shield is especially advantageous, since its lower edge may be stopped in convenient position to be raised above the printing line by line-spacing the platen one or two times, the number of line-spacing operations needed being determined whether the machine is set for single or double line-spacing.

Other features and advantages will hereinafter appear.

In the accompanying drawings,

Figure 1 is a fragmentary perspective view of the carriage of an Underwood typewriter machine, having my invention applied thereto, showing the work-sheet in operative position overlying the record-sheet interleaved with carbon.

Figure 2 is a fragmentary cross-sectional view of the same.

Figure 3 is a fragmentary front view of the same, showing the work-sheet advanced for printing a second line of characters thereon, the shield being lowered below the second line.

Figure 4 is a diagrammatic view of a sheet or web of bank-check forms.

A typewriter-platen 10, on a shaft 11, mounted in the carriage side frames 12, may have line-spacing means including a finger-wheel 13 and a ratchet-wheel 14, the latter being operated by finger-piece mechanism, not shown. Two feed-rolls 17, engaging against the upper side of the platen 10, are carried by fingers 18 fastened to arms 19, the latter being slidably and pivotally mounted on a platen-carriage-rod 20. Feed-rolls 21 and 22 are arranged to be thrown against or away from the lower side of the platen 10 by means not shown. A paper-table 23 may have an apron-extension 24 under the platen. The above-described parts may be the same as on an Underwood typewriter machine.

A paper-table or chute 30, having two forwardly-extending flanges 31 arranged for serving as side gages for work-sheets, may be supported by two arms 32 fast on side frames 12, so that the lower edge 33 of the table may be in close proximity to the platen, at a point, say 45 degrees above the printing line, the latter being indicated by a type 34. Back or body portions 35 of the paper-table may be slightly inclined rearwardly. Each of the flanges 31 may have a narrow, lengthwise slot 36, in close proximity to the face of the paper-table 30. An interponent or shield 38 of substantially rectangular shape, made preferably of relatively hard, flexible cardboard, may have two laterally-projecting stop-pieces 39, which may extend outward through the slots 36, and serve to limit the upward and downward movements of the shield, which is arranged on the

face of the table 30, to fit loosely between the flanges 31 and be guided thereby. The stop-pieces engaging in the slots also serve to prevent displacement of the shield from the table. The shield may extend downwardly from the lower edge 33 of the table to be substantially tangent to the platen 10 at the printing line thereof, with its lower edge 40 below the printing line (see Figure 3) when the lower sides of the projecting pieces 39 are down against the lower ends of the slots 36.

A plurality of bank-checks 50^a, 50^b, etc., may be fastened one below another along perforate lines 51, to form a check-sheet 52, having a width slightly less than the distance between the flanges 31. For conveniently typewriting characters on the checks and making a condensed record of them at the same time, the check-sheet 52 with a wider underlying record-sheet 53 and an inter-leaved carbon-sheet 54 may be inserted around the platen 10 from the rear in the usual way. The three sheets may be advanced together as far as the lower edge 40 of the shield 38. There the check-sheet 52 and the carbon-sheet 54 may be passed in front of the shield 38 and advanced to bring the first or leading check 50^a in position for typing the payee's name and the numerical amount of the check. The record-sheet will pass below and behind the shield, and under upper feed-rolls 17 positioned at either side of paper-table 30. In this position, friction between the work-sheets and the shield may hold the lower edge 40 of the shield 38 above the printing line, and permit characters typed on the check 50^a to be carbon-copied on the record-sheet 53 (see Figures 1 and 2). The payee's name and the numerical amount of the first check may be typed in one line as usual. The check, carbon and record sheets may now be line-spaced together to bring the check 50^a in position for writing the amount of it in words below the payee's name. The lower edge 40 of the shield 38 may be pushed down below the printing line (see Figure 3), and stopped at a certain predetermined point by arrangement of the stop-pieces 39 in the slots 36. After writing the amount of the check in words, which the shield prevents being carbon-copied, the carriage may be moved to the right by a carriage-finger-piece, not shown, and the platen 10 line-spaced thereby, as usual in an Underwood typewriter. The platen 10 may be further line-spaced in the usual way, if necessary, for raising above the printing line the shield 38, which, at the beginning of these line-spacing operations, is held tightly between the carbon-sheet 54 and the record-sheet 53, and is moved upwardly by friction of the moving sheets. The feed-rolls 21 and 22 may now be thrown off, and the check-sheet

pulled ahead, to bring the second check 50^b to proper position for having its payee's name and numerical amount typed, as was done on the first check 50^a. It can be readily seen that employment of the herein-disclosed means permits lines of record-data of checks to be conveniently spaced much nearer on a record-sheet than they appear on the overlying check-sheet. The record-sheet 53 is held against movement by the feed-rolls 75 while the second sheet is advanced. For holding the typed portion of the check-sheet 52 against the face of the table 30, a finger-piece 55, more fully described in the patent to Jesse A. B. Smith, No. 1,487,671, dated March 18, 1924, may be used. Checks may be severed from the sheet or web 52 when they have been typed, and advanced above the paper-table 30, or after the sheet has been removed from the machine, and the checks have been dated and signed.

Variations may be resorted to within the scope of the invention, and portions of the improvements may be used without others.

Having thus described my invention, I claim:

1. In a typewriting machine, the combination with a carriage and a platen, of a paper-table mounted on said carriage above said platen and having forwardly-extending side flanges arranged with lengthwise slots, and a shield movable up and down over the face of said table and arranged to extend downwardly therefrom between work-sheets to be substantially tangent to said platen at the printing line thereof, said shield having two lateral projecting stop-pieces, one at each side, arranged to extend through said slots for limiting the upward and downward movement of said shield. 100

2. In a typewriting machine, the combination with a carriage and a platen, of a paper-table mounted on said carriage above said platen and having forwardly-extending side flanges arranged with lengthwise slots, and a type-blow-receiving shield movable up and down over the face of said paper-table between said flanges and arranged for engaging with the same whereby the lower edge of the shield may be stopped a certain short distance below the printing line of said platen. 110

3. In a typewriting machine, the combination with a carriage and a platen, of a paper-table mounted on said carriage above said platen and having forwardly-extending side flanges, and a type-blow-receiving shield movable up and down over the face of said paper-table between said flanges, said flanges being arranged for engagement with said shield whereby both the upward and downward movements of the latter may be limited. 125

4. In a typewriting machine, the combination with a carriage and a platen, of a

paper-table mounted on said carriage above said platen and having forwardly-extending flanges provided with narrow lengthwise slots near the face of said table, the lower 5 edge of said table being arranged to terminate within close proximity to said platen a short distance above the printing line.

5. In a typewriting machine, the combination with a carriage and a platen, of a 10 paper-table mounted on said carriage above said platen, a shield movable on said table within fixed limits and extending downwardly between a work-sheet and underlying record-sheet below the printing line of 15 said platen, a finger-piece for holding said work-sheet against the upper portion of said shield, and means for raising said shield by friction with said work-sheets above said printing line.

20 6. In a typewriting machine, the combination with a carriage and a platen, of a paper-table mounted on said carriage above said platen, a shield movable on said table within fixed limits and extending downwardly 25 between a work-sheet and underlying record-sheet below the printing line of said platen, a finger-piece for holding said work-sheet against the upper portion of said shield, and line-spacing mechanism arranged for rotating said platen whereby said 30 work-sheets when advanced will frictionally engage said shield and raise same to its upper fixed limit.

7. In a typewriting machine, the combination with a carriage and a platen, of a 35 paper-table mounted on said carriage and having forwardly-extending side flanges arranged for serving as side gages for work-sheets and being provided with narrow 40 lengthwise slots, and a shield movable up and down over the face of said table between

said flanges and extending downwardly to be substantially tangent to said platen at the printing line thereof, said shield having lateral stop members projecting through said 45 slots and arranged for allowing a limited movement of the shield, and preventing its misplacement from said table.

8. In a typewriting machine, the combination with a carriage and a platen, of a 50 paper-table mounted on said carriage above said platen and having forwardly-extending side flanges provided with lengthwise slots, a feed-roll on each side of said table engaging the upper side of said platen, and a 55 shield movable over the face of said table and extending downwardly between a carbon-sheet underlying a check-sheet and an underlying record-sheet to tangentially engage said platen on the printing line thereof, said check-sheet and carbon-sheet being 60 arranged to pass in front of said shield, and said record-sheet being arranged to pass behind said shield and under said feed-rolls whereby said check-sheet may be advanced 65 upwardly over said table while said record-sheet is held stationary, said shield having lateral stop pieces projecting through said slots and arranged for limiting the up-and-down movement of said shield.

9. In a typewriting machine, the combination with a carriage, a platen, and types, of a shield arranged to tangentially engage said platen on the printing line thereof between a work-sheet and an underlying record-sheet whereby the blows of said types may not affect said record-sheet, and means mounted on said carriage for guiding said shield up and down between said work-sheets and limiting its movement in each direction. 75
